UNITED STATES PATENT OFFICE.

DAVID SCHRAG, OF NEW YORK, N. Y.

COMBINATION TOOL.

Application filed April 7, 1921. Serial No. 459,230.

To all whom it may concern:

Be it known that I, DAVID SCHRAG, a citizen of the United States, and resident of New York City, in the county of New York 5 and State of New York, have invented certain new and useful Improvements in Combination Tools, of which the following is a specification.

My invention relates to combination tools 10 and has for its object to provide a simple and efficient tool of this class in which a plurality of elements of special utility in connection with the ignition system of an internal combustion engine are conveniently 15 combined. Other more specific objects of my invention will appear from the description hereinafter and the features of novelty will be pointed out in the appended claim.

In the accompanying drawings which 20 illustrate an example of my invention without defining its limits, Figure 1 is an elevation of the combination tool, and Fig. 2 is a cross-section thereof on the line 2—2 of Fig. 1.

As shown, the combination tool comprises 25 a main section or shank 5, the free end of which is fashioned in the form of a wrench 6 dimensioned with special regard to the customary hexagonal or similar elements 30 whereby, for instance, the breaker points of distributing blocks included in ignition systems of the well-known type are generally secured in place. The shank 5 is further provided with continuing members 7 35 spaced apart in parallel relation and having their free ends turned inwardly to constitute an end member 8 and thereby form a closed recess in which an abrasive device, preferably in the form of a composition 40 stone 9, is secured in any convenient manner. In the preferred arrangement the stone 9 is grooved to fit the inner surfaces of the members 7 and is held against removal by the inturned ends 8 thereof, as shown. The 45 transverse thickness of the stone 9 corresponds to the width of the members 7 and 8, said stone being of a size and shape otherwise to fit the recess formed by said members 7 and 8. The tool further comprises 50 gage plates 10 and 11 constructed of sheet metal having a thickness corresponding, for instance, to the distance between the spark or breaker points of a distributing block or, in other words, to the spark gap thereof, 55 the plate 10 being, for instance, $\frac{3}{16}$ of an inch in thickness while the plate 11 is, for

instance, $\frac{1}{8}$ of an inch thick, these two dimensions representing the distances apart at which the breaker points of such distributing block provide the most efficient 60 spark. The plates 10 and 11 are of a size to completely cover the opposite faces of the stone and are movably incorporated in the tool, for instance by being pivoted at 12, so as to be capable of covering and uncovering 65 said stone as desired.

The plates 10 and 11 in addition, therefore, to serving as gages to correctly gage the spacing of the breaker points, serve further as protectors whereby the effective 70 faces of the stone 9 are protected when not in use. This is of importance to prevent injury to or breaking of said stone when the combination tool is carried in a tool box with numerous other tools and implements. 75 The stone 9, it will be understood, is useful for rubbing off all rough and projecting spots from the spark points and for adequately and efficiently cleaning the same. Furthermore, the gage plates 10 and 11, 80 when in their normal positions, constitute continuations of the shank 5 and form a handle therefor or complete the handle structure whereby the wrench 6 may be manipulated. The wrench 6 is of a size to 85 readily fit the nuts of existing ignition devices and may be efficiently utilized to adjust the same for securing breaker points and the like in position and to disconnect the same. 90

The combination tool provides a serviceable implement which may be readily carried about and in which a plurality of instrumentalities are combined in a single structure; in other words, the tool in its 95 illustrated form provides a wrench, a stone, and gages adapted particularly for adjusting the breaker points of Delco, Bosch, and Isman ignition systems, and in fact all electric systems in which platinum and tungsten points are used. 100

The tool makes it unnecessary to remove the breaker points or their equivalent from the ignition system when it is desired to clean the same and at the same time guarantees a proper adjustment thereof in a simple and efficient manner. 105

While the tool is intended primarily for use as herein indicated, it is obvious that it may be otherwise utilized to advantage if 110 desired.

Various changes in the specific form

shown and described may be made within the scope of the claim without departing from the spirit of my invention.

I claim:

- 5 A tool comprising a shank provided at one end with a through recess extending lengthwise thereof, an abrasive stone fitted in said through recess and having its opposite faces adapted to be exposed, and plates
10 pivotally mounted upon said shank and nor-

mally lying in registry with said stone to cover the opposite surfaces thereof, said plates being pivotally movable to positions transverse to said shank to uncover the surfaces of said stone.

Signed at the city of New York in the county of New York and State of New York this 1st day of April, 1921.
